UNITED STATES PATENT OFFICE.

WILLIAM EMERY DAVIS, OF PORTLAND, OREGON.

DEVICE FOR PRINTING ON WRAPPING-PAPER ROLLS.

1,112,421.

Specification of Letters Patent. Patented Sept. 29, 1914.

Application filed March 19, 1913. Serial No. 755,309.

To all whom it may concern:

Be it known that I, WILLIAM EMERY DAVIS, a citizen of the United States, residing at Portland, in the county of Multnomah and State of Oregon, have invented 5 certain new and useful Improvements in Devices for Printing on Wrapping-Paper Rolls, of which the following is a specification.

10 My invention relates to devices for printing wrapping-paper, whereby one end of the paper as it unwinds from the roll passes around several additional rolls and a portion of said paper is printed by type arranged in such a manner as will be herein-after fully explained.

15 The object of my invention is to provide a device of this kind that is simple in construction, inexpensive in manufacture, durable, and efficient in action; and further to provide a printing device that will print the name of the dealer on his wrapping-paper at every revolution of the roll to which the type is attached.

20 With these objects in view, my invention consists of certain novel features of construction and arrangements of parts as will be hereinafter more fully described in the following specification and particularly 25 pointed out in the appended claim.

30 In order to fully comprehend my invention and the parts to which it relates, reference must be had to the accompanying drawing which forms a material part of the 35 application, of which:—

Figure 1 is a front view of my invention showing a section through the paper on line A A of Fig. 2; the remainder of the roll of paper being removed:—and Fig. 2 40 is an end elevation of same showing the means of attaching the paper thereto.

Like characters of reference indicate like parts in the figures of the drawing, of which:—

45 The numeral 2 indicates a base-plate to which are fastened standards 3 to which is pivoted roll 4 on which is wound paper 5. To the rear of standards 3 are attached another pair of standards 6, which also fasten 50 to base-plate 2, and with brackets 7 fastened thereto. Pivoted to standards 6 are spiders 8 which are connected by roll 9. Passing longitudinally of roll 9 is a bar 10, the peripheral portion of which registers with 55 segmental slots 11 in the periphery of spider 8; said segmental slots, and the periph-

eral portion of bar 10 being adapted to receive type which is represented by segment 12. Standards 6 have also pivoted thereto an idler-roll 13, by means of pins 14, to which are also pivoted hangers 15, to which is rotatably mounted inking-roll 16; said inking-roll being held close to the type by means of springs 17 which are attached to hangers 15 and standards 6. 65

Pivoted between brackets 7 are rolls 19; 20 and 21 respectively, for the purpose of reducing the friction in unrolling paper 5 and causing said paper to unwind with little effort on the part of the operator. 70

In order to operate my invention the free end of paper 5 must pass over idler-roll 13, under roll 19 and over rolls 20 and 21 respectively, and downward under guide 22 as illustrated in Fig. 2. The operator then 75 pulls said paper forward and the friction of said paper between idler-roll 13 and the periphery of spiders 8 causes said spiders to revolve toward inking-roll 16 and idler-roll 13. When the type portion 12 passes inking-roll 16, said inking-roll is pressed firmly against said type by means of springs 17, after which said type prints the paper as it passes over idler-roll 13, and so continues to print at each successive cycle of 80 85 the type.

My invention can be constructed of any material and made of any size deemed suitable for such a mechanism, and while I have described and illustrated a preferred form 90 of construction and combination of elements deemed suitable for such a device, I desire to include in this application all mechanical equivalents and substitutes that may be fairly considered to come within the scope 95 of my invention as defined and specified in the appended claim.

Having thus fully described my invention so that others skilled in the art to which it appertains, may be enabled to construct and 100 use the same, what I claim and desire to secure by Letters Patent, is:—

In a device of the character described, the combination with a base-plate with a pair of vertical standards at the front portion of 105 said base-plate, a pair of vertical standards to the rear of the aforesaid vertical standards, revoluble spiders supported by said rear standards, means to connect said spiders, a portion of said spiders being adapted to receive type, a roll revolubly mounted to the rear standards immediately below 110

said spiders, hangers pivoted to the rear standards, an inking roll of tenacious material revolubly mounted to said hangers, springs attached to said rear standards and 5 said hangers for the purpose of yieldingly supporting said inking roll, brackets forming approximately two right-angles fixed to said rear standards, and revoluble means carried by said brackets to guide paper, said

paper being attached intermediate the forward standards, substantially as set forth.

In testimony that I claim the foregoing as my own, I hereunto affix my signature in the presence of two subscribing witnesses.

WILLIAM EMERY DAVIS.

Witnesses:

PETER HABERLIN,
W. E. THRESHER.
